UNITED STATES PATENT OFFICE.

CLARENCE E. GOINGS, OF PHILADELPHIA, PENNSYLVANIA, ASSIGNOR, BY MESNE ASSIGNMENTS, TO THE POSITION-LIGHT SIGNAL COMPANY, A CORPORATION OF MAINE.

APPARATUS FOR SUPPRESSING FALSE SIGNALS.

1,335,330.

Specification of Letters Patent. Patented Mar. 30, 1920.

Application filed March 22, 1915. Serial No. 16,176.

To all whom it may concern:

Be it known that I, CLARENCE E. GOINGS, a citizen of the United States of America, and a resident of Philadelphia, Pennsylvania, have invented certain new and useful Improvements in Apparatus for Suppressing False Signals, of which the following is a specification.

In the use of a light signal for daylight indication, difficulties are met with due to the tendency of internal parts of the several units making up the signal to reflect back light falling on them in such a way as to show an apparently lighted unit, whereas, 15 in fact the unit is not lighted.

I refer, as an example of a daylight signal, to what is known as the "position-light" signals recently installed in the Pennsylvania railroad near Philadelphia, and in 20 which the indication is given both for day and night signaling by the relative position of light-emissive surfaces. Each light surface forms part of a corresponding unit which comprises a source of illumination, 25 either in the form of a lamp (or it might be in the form of a reflector serving to reflect the light from a common source); a lens for concentrating and directing the emergent beam, and a cover glass to protect the 30 lens, and by preference a reflector to concentrate the rays and throw them out through the lens.

With units of this character a part of the light falling upon the cover glass from the front thereof may, under some conditions, and especially when the sun is near the opposite horizon, be reflected from the front surface thereof, and so illuminate it that it appears as if it were illuminated by and 35 from the source of light located in its rear. Again, another part of such light at such time may pass farther into the unit and, after being reflected and concentrated by internal surfaces thereof, be reflected back to 40 likewise cause a false indication. With standard signals the difficulties pointed out may to a great extent be avoided by the use of hoods which, by projecting forwardly over the cover glasses, shield the latter from 45 the sun, but with "dwarf" signals the use of hoods is impossible.

My invention has for its object to overcome the difficulties above pointed out as due to reflection, and while it is especially 50 applicable to dwarf-position-light signals, it

is capable of use in connection with standard signals of the same type, or even with the colored light signals now in common use, in so far as the difficulties above pointed out may be present in such signals.

The process and means employed by me for the purpose stated will be described in connection with the accompanying drawing which is a sectional view showing my invention as applied to a signaling unit of a 65 position-light signal, as is shown in an application filed by William Churchill and Alexander H. Rudd in the United States Patent Office, July 13, 1914, serially numbered 850,817.

In this drawing, which illustrates one embodiment of the invention, 1 is a suitable lens located in an opening in the case 2. In the case behind the lens is a lamp 3, while located above the lamp is a reflector 4. In 70 front of the lens is a concavo-convex cover glass 5, the cover glass and lens being held within the opening of the case by a mounting 6. The face 7 of the casing is preferably blackened to kill reflection therefrom and to 75 afford a background against which the illuminated unit may be seen.

In the accompanying drawings, the reflector is shown as above the lamp, and is adapted in connection with the lens used, 80 to reflect the rays diverging upwardly and rearwardly from the lamp in such a manner that the beam from the lens spreads downwardly so as to be seen from the track close to it, this being advisable in a "standard" 85 signal. It is obvious that in case the signal is a dwarf signal, that is to say, a signal located near the ground, and which is to be seen from above, the location of the reflector will be changed, so that in connection 90 with the lens used, the signal can be seen from above when near the signal.

I have found that by interposing between the lens and cover glass one or more thicknesses of thin fabric 8, the reflections, which 100 it is the object of this invention to overcome, are either suppressed or reduced to such an extent as to be unobjectionable. I have found that black chiffon is suitable for the purpose indicated, and that a unit, having 105 the chiffon at the point indicated, appears, even when viewed with a strong light falling thereon, as not only unilluminated, but as black, simulating the appearance of the blackened surface of the case.

Inasmuch as the fabric absorbs a certain portion of the light emanating from the lamp 3 in signaling, care should be had to have the lamp of sufficient high candle-
5 power to give illumination effective for the desired signaling distance.

It will be noted that light passing through the cover glass from the front and tending after passing therethrough to be reflected back through the cover glass by the interior faces of the unit, (such as of the lens of the lamp and of the reflector, all of which may serve as condensing elements therefor), is when the fabric is employed, compelled to pass therethrough. The fabric either absorbs to a greater or less extent these relatively feeble beams incident thereon, before they are concentrated by the reflecting and condensing 10 faces in the rear thereof, or else, by diffusion, so alters the direction of the incident rays as to prevent the same being concentrated by the reflecting faces, to give the 15 false indication. In either case, the incident beams are destroyed and broken up.

It will be noted that the light absorbing medium which is permanently located in front of the lens, does not cover such unit in the sense of shutting off the beam produced by light originating within the unit, 20 its nature being such that it at the same time prevents the passage of such light while intercepting light falling thereon from the front sufficiently to prevent reflections from 25 the unit.

I am aware that it is old to interpose in the path of a beam of light, issuing from a signaling lamp a colored roundel or a col-

ored cloth screen for the purpose of giving a characteristic color indication to the signal, but so far as I know such prior structures have not contemplated or embodied the prevention of the giving false signal indication by incident light, as is herein described.

By the above illustration and description of a specific embodiment of my invention, which is made in accordance with the requirements of the statutes, I do not desire to be understood as limiting my invention thereto, as the latter is susceptible of other embodiment, but what I do claim is,—

1. As a means of absorbing light falling upon and into a signal unit, having light-reflecting and condensing surfaces in its interior, a light absorbing medium located in front of such reflecting and condensing surfaces, and intercepting light on its passage thereto, but permitting the passage of light of greater intensity originating in the unit. 55

2. As a means of absorbing light falling upon and into a signal unit having light-reflecting and condensing surfaces in its interior, a light-absorbing medium consisting of a layer of woven fabric located in front 65 of such reflecting and condensing surfaces and intercepting light on its passage thereto, but permitting the passage of light of greater intensity originating in the unit.

In testimony whereof I have hereunto signed my name in the presence of two witnesses.

CLARENCE E. GOINGS.
